LOUIS A. PAGE, OF PROVIDENCE, RHODE ISLAND, ASSIGNOR OF ONE-HALF TO EDWIN B. EVANS, OF PROVIDENCE, RHODE ISLAND.

SAFETY-CATCH.

1,376,899.

Specification of Letters Patent.

Patented May 3, 1921.

Application filed October 8, 1920. Serial No. 415,661.

To all whom it may concern:

Be it known that I, LOUIS A. PAGE, a citizen of the United States, residing at Providence, in the county of Providence and State of Rhode Island, have invented 5 certain new and useful Improvements in Safety-Catches, of which the following is a specification.

This invention relates to improvements in 10 safety catches for pins such as cuff pins, beauty pins and the like.

My present invention has for its object to 15 provide an improved form of keeper or gate member which is designed to close the opening in the keeper-member of the catch and effectually prevent the joint of the pin-stem from being inadvertently removed therefrom.

The nature and advantages of the invention 20 will be better understood when the following detail description is taken in connection with the accompanying drawings, the invention residing in the combination and arrangement of parts as claimed.

In the drawings forming part of this 25 specification, like numerals of reference indicate similar parts in the several views and wherein:—

Figure 1 is a side elevation of a pin-body 30 illustrating my improved catch as retaining the pointed end of a pin-stem.

Fig. 2 is a plan view showing the double hook-shaped arms of the keeper-member as 35 cut from sheet stock.

Fig. 3 is a side elevation of the keeper-member with its two arms folded together.

Fig. 4 is the same as Fig. 3 but with one 40 of the arms removed, being sectioned at its base.

Fig. 5 is a perspective view of the gate-member of the catch.

Fig. 6 is an edge view of the catch-member, showing the gate-member in closed position therein.

Fig. 7 is a side view of my improved 45 catch-member, showing the gate in closed position.

Fig. 8 is a side view of my improved 50 catch-member, showing the gate in open position.

Fig. 9 is an edge view showing the rear of my improved catch.

Fig. 10 shows a modification in which the 55 free end of the gate member is offset laterally slightly to extend past the overlapping

portion of the hook end without notching the same.

With reference to the drawings, 10 designates the base or body portion of a pin to which the usual pin-stem 11 is pivoted in 60 the jointed member 12, the opposite end of the pin-stem being locked and retained in my improved safety catch member 13. The body or keeper portion of this catch-member, is preferably struck from sheet stock, 65 first into the form illustrated in Fig. 2, providing two hook-shaped arms 14 and 15 which are subsequently folded up against each other on the center line 16.

The inner surface 17 of each of these arms 70 is preferably recessed slightly so that when the two arms are folded together a slot 18 will be provided between them for the reception of a gate-member, presently described, and when these arms are so folded they provide 75 a hook-shaped body or keeper portion having an open mouth 19 for the reception of the pointed end of the pin-stem 11.

In forming the hook-shaped ends of these arms I preferably make the end of the arm 80 15 slightly shorter than that of the arm 14 thereby causing them to overlap one beyond the other.

The gate-member 20 is preferably formed 85 in crescent shape and of thin stock, the same being pivoted at 21 to swing in the slot 18 between the side arms 14 and 15. The free end of this gate is offset as at 22 to serve as a stop, to engage the inner surface of one of the side arms of the keeper and limit the 90 outward or opening swing of the gate.

It will be noted that when the gate is in closed position its free end swings past the extending portion 14 of one of the arms of the keeper and abuts against the end of the 95 opposite arm, whereby a broken joint is formed to prevent an outward strain on the pin-stem from acting directly upon the free end of the gate to move it toward open position. In other words such an outward strain 100 will be taken by the extending end of the keeper instead of being exerted upon the swinging gate.

In order to hold the gate in open position I have provided a slight protuberance 23 105 on the gate which will frictionally engage the wall of the slot in swinging past it. This protuberance also serves to hold the gate in locked position and prevents accidental opening of the same.

The base portion 24 of the keeper-member may be secured in any suitable way to the body of the pin or member on which it is used.

5 The inner edge of one of the arms of the keeper is shown as being notched as at 26 to receive the outturned end 22 of the gate.

In some cases I offset the end of the gate member laterally as shown at 25 in Fig. 10, 10 whereby it will pass by the extending portion 14 of the hook end and so save notching the same as shown in Fig. 6. Then again this offset on the end of the gate 15 serves as a friction to retain it in its slot when swinging back to open position.

My improved safety catch is simple, practical and inexpensive in construction and by 20 its use a pin-stem may be securely retained in the catch against accidental removal therefrom.

The foregoing description is directed solely toward the construction illustrated, but I desire it to be understood that I 25 reserve the privilege of resorting to all the mechanical changes to which the device is susceptible, the invention being defined and limited only by the terms of the appended claims.

I claim:

30 1. A safety catch comprising a keeper-member having two integral hook-shaped arms folded upon each other with a space between them, and a gate-member pivoted to swing in said space between said arms

from the back of the hook toward the front 35 thereof to close it.

2. A safety catch comprising a keeper-member formed of a pair of integral hook-shaped arms folded together, the inner side walls of said arms being recessed to provide 40 a slot between them, and a gate-member pivoted to swing in said slot from the back of the hook toward the front thereof to close it.

3. A safety catch comprising a keeper-member having two integral hook-shaped arms folded upon each other with a space 45 between them, a gate-member pivoted to swing in said space between said arms from the back of the hook toward the front thereof, the free end of said gate-member being offset to form a stop to limit the opening 50 swing of said gate.

4. A safety catch comprising a keeper-member formed of a pair of hook-shaped 55 arms set side by side, the inner side walls of said arms being spaced to provide a slot between them, the end of one hook arm extending beyond that of the other, and a gate-member pivoted to swing between said 60 arms from the back of said hook toward the front thereof to close it, the free end of said gate being adapted to swing past the longer hook and abut against the shorter end thereof when closed.

65 In testimony whereof I affix my signature.

LOUIS A. PAGE.
